A. WASEMANN

SHIFTING RODS FOR HARP ATTACHMENTS

Filed Sept. 20, 1923

INVENTOR
Albert Hasemann
By *H. C. Dunlap*
ATTORNEY

UNITED STATES PATENT OFFICE.

ALBERT WASEMANN, OF WHEELING, WEST VIRGINIA.

SHIFTING RODS FOR HARP ATTACHMENTS.

Application filed September 20, 1923. Serial No. 663,725.

To all whom it may concern:

Be it known that I, ALBERT WASEMANN, a citizen of the United States of America, and resident of Wheeling, county of Ohio, and 5 State of West Virginia, have invented certain new and useful Improvements in Shifting Rods for Harp Attachments, of which the following is a specification.

This invention relates broadly to harp attachments for player pianos, and more specifically to an improved shifting device for the felt-carrying frame of such attachments.

The primary object of the invention is to provide a support for the carrier bar or frame upon which are mounted the felt strips of a harp-attachment, said support being shiftable for moving such carrier frame to and from operative position and being adjustable in length to suit frames located at 20 different distances from the front edge of the tops of the roll boxes.

In describing the invention in detail, reference is herein had to the accompanying drawings, in which—

25 Figure 1 is a transverse section of the roll box and the harp attachment of a player piano, illustrating the application of my invention;

30 Figure 2 is an enlarged side elevation of the invention, detached; and—

Figure 3 is a detail section on line 3—3, Fig. 1.

Referring to said drawings, 1 indicates the horizontal top of the usual form of roll box employed in player pianos, 2 a piano wire and 3 a sounding hammer. Located in front of and adjacent to the piano wires 2 is a horizontal bar 4 to which is suitably attached the upper ends of the felts 5 which, 35 in the use of the harp attachment, are interposed between the hammers 3 and the wires 2, said bar being carried, as ordinarily, by the forward ends of pivoted arms 6 and being adapted to be swung vertically to and 40 from the withdrawn or inoperative position shown in full lines in Fig. 1 from and to, respectively, the operative position indicated in broken lines in said figure.

The device by means of which shifting of 45 said bar is effected, and which constitutes the present invention, comprises two rod sections 7 and 8 which have their adjacent end portions disposed horizontally in parallel relation and attached rigidly by a coupling 9. The outer rod section 7 has the body portion thereof of straight form and rotatably

mounted in a horizontal position upon the top 1 of the roll box, keeper clips 10 being herein shown as mounted upon said top and forming bearing-like retaining members in 60 which said rod section is rotatable. The body portion of the rod section 8 is likewise straight and horizontally disposed. The inner end portion of said section 8 is formed in crank shape, an intermediate portion 8^a 65 being turned at substantially a right angle to the body and a terminal portion 8^b being disposed horizontally. Attached to said terminal portion is the upper end of a chain 11 or other suitable form of suspension device 70 which has its lower end attached to the bar 4.

As is obvious, when the crank-shaped inner end of the rod section 8 occupies the upright position shown in Fig. 1, the harp attachment which includes the bar 4 is supported in elevated inoperative position. When, however, the rod is rotated to the position indicated in dotted lines in said figure, the bar 4 is permitted to gravitate to operative position.

The outer end portion of the rod section 7 is bent to form an arm 7^a disposed at right angles to the body of said section, a short inwardly or forwardly directed portion 7^b and a terminal portion 7^c, the latter preferably being parallel to the arm 7^a and forming a finger piece whereby the rod is grasped for effecting rotation thereof. The arm 7^a, which lies closely in front of the top 1 of the roll box is of a length materially 90 greater than the thickness of said top, thus adapting the device for rotation between the full line and the dotted line positions shown in Fig. 3, or throughout the part of a revolution required to shift the harp-attachment 95 bar 4 from one limit of movement to the other. At each of said limits of movement the forwardly directed portion 7^b of the rod 7 closely underlies the top 1 of the roll box, as shown in Fig. 3.

The coupling 9 consists of a substantially cylindrical member having parallel holes 12 extending diametrically therethrough for the reception of the parallel body portions of the rod sections 7 and 8. Set screws 13 directed through the opposite ends of said coupling are adapted for adjustment into bearing relation to said body portions for maintaining the latter in adjusted positions. As is obvious, the rod sections may be adjusted to give the rod any length required.

A pin or stud 14 carried by said outer

section 7 at a suitable point abuts one of the keepers 10 and prevents outward shifting of the rod.

What is claimed is—

- 5 1. The combination with a harp attachment for pianos, including a vertically shiftable felt-strip-carrying bar, of a rotary bar supporting and shifting device comprising two complementary rod sections mounted
- 10 horizontally at right angles to said bar, the inner rod section having a crank formed on its inner end, a suspension member depending from said crank and supporting said bar, and the outer end section of said rod
- 15 being mounted for rotary movement, and a coupling for the adjacent end portions of said rod sections providing for relative adjustment of the latter.
- 20 2. The combination with a harp attachment for pianos, including a vertically shiftable felt-strip-carrying bar, of a rotary bar supporting and shifting device comprising a rod made in two substantially aligned sections, the inner rod section having a crank formed on its inner end, a suspension member depending from said crank and supporting said bar, and a coupling for the adjacent end portions of said rod sections providing for relative lengthwise adjustment of the latter.
- 25 30 3. The combination with a player-roll box and a harp attachment for pianos, said attachment including a vertically shiftable felt-strip-carrying bar, of a rotary bar sup-

porting and shifting device comprising a rod made in two substantially aligned sections, the inner rod section having a crank ⁴⁰ formed on its inner end, a suspension member depending from said crank and supporting said bar, and a coupling for the adjacent end portions of said rod sections providing for relative adjustment of the latter, ⁴⁵ the outer end section of said rod being mounted on said box for rotary movement and having its outer end shaped to form means engageable with a fixed part of said box whereby the extent of such movement ⁵⁰ is limited.

4. The combination with a player-roll box and a harp attachment for pianos, said attachment including a vertically shiftable felt-strip-carrying bar, of a rotary bar supporting and shifting device comprising a rod formed in two complementary substantially aligned sections, the inner rod section having a crank formed on its inner end, a suspension member depending from said crank and supporting said bar, and a coupling for the adjacent end portions of said rod sections providing for relative lengthwise adjustment of the latter, the outer end section of said rod being mounted on said ⁶⁰ box for rotary movement and having its outer end shaped to form an angularly disposed arm and a forwardly directed portion, the latter located parallel to and at a spaced distance from the body of said outer ⁶⁵ section.

In testimony whereof, I affix my signature.

ALBERT WASEMANN.
